FOREIGN PATENT DOCUMENTS

EM 005616950-0002 * 8/2018

Primary Examiner — Paula Allen Greene(74) *Attorney, Agent, or Firm* — Lorraine Hernandez; Kegler Brown Hill + Ritter Co LPA(57) **CLAIM**

The ornamental design for a pair of electronic earmuffs, as shown and described.

DESCRIPTION

FIG. 1 is a top front perspective view of a pair of electronic earmuffs showing my new design;

FIG. 2 is bottom rear perspective view of the pair of electronic earmuffs illustrated in FIG. 1;

FIG. 3 is a front view of the pair of electronic earmuffs illustrated in FIG. 1;

FIG. 4 is a back view of the pair of electronic earmuffs illustrated in FIG. 1;

FIG. 5 is a right side view of the pair of electronic earmuffs illustrated in FIG. 1;

FIG. 6 is a left side view of the pair of electronic earmuffs illustrated in FIG. 1;

FIG. 7 is a top view of the pair of electronic earmuffs illustrated in FIG. 1; and,

FIG. 8 is a bottom view of the pair of electronic earmuffs illustrated in FIG. 1.

The broken line disclosure in the views represents portions of pair of electronic earmuffs, which forms no part of the claimed design.

1 Claim, 6 Drawing Sheets---
